UNITED STATES PATENT OFFICE

2,132,478

SIGN FOR HIGHWAYS

Albert D. Ide, Chicago, Ill.

Application May 3, 1938, Serial No. 205,743

3 Claims. (Cl. 40—125)

My present invention relates to signs for the intersections of highways with railroads or other highways. The increased speed of motor vehicles over horse drawn vehicles renders it desirable to utilize every facility for the prevention of highway accidents. It is believed that the indication of the direction from which danger may approach will contribute to the safety of driving without unduly complicating the nature of the sign or signal which is employed for indicating the direction of approach of possible danger.

It has been my object to provide instrumentalities which may be adjusted and arranged to indicate the relations of intersecting highways or intersections of highways with railroads which will permit the sign to be uniformly and economically constructed in a factory and will only require simple adjustment and arrangement when installed to indicate any one of a great many relations which intersecting highways and railroads may have to each other.

I attain the foregoing object by means of the accompanying drawing in which,—

Fig. 1 is a front view of a sign embodying my invention;

Fig. 2 is a fragmental side elevation of the sign shown in Fig. 1;

Fig. 3 is a detail, to an enlarged scale, showing means of suspension of sign;

Fig. 4 is a fragmental detail of a modified form of annulus;

Figs. 5 and 6 are examples of varying forms of intersections which may be shown by my sign;

Fig. 7 is a detail side elevation of a modified form of sign;

Fig. 8 is a front view of the sign shown in Fig. 7, and

Fig. 9 is a side view of a commercial form of reflector which may be employed with my sign.

The horizon at the location of the intersection is schematically illustrated by an annular band A located peripherally of the circular or disc like sign. This annular peripheral band A may be a separate piece of material, as shown in Fig. 1 or it may be an integrally extending flange, such as at A' in Fig. 7 of a disc, the central portion of which is slightly depressed to form the perforations of the central disc B. About the annulus A, at distances of approximately 22½ degrees, I provide perforations C which are for the receipt of the threaded stems extending from the bases of reflector bulls-eyes which are, not infrequently, used for reflecting back the illumination of the driving lights of motor vehicles and which can now be obtained on the market in diverse

forms and sizes. I provide the perforations C, at 22½ degrees apart, so that the annular band will need but little circumferential adjustment to bring one of the perforations at the point of the horizon from which, or to which, the 5 intersecting road or railroad approaches. Another reflector is positioned in the portion of the peripheral band over which the other end of the approaching intersecting highway or railroad either comes into view or departs from view as 10 the case may be.

The central disc B has provided therein radial lines of perforations D similar to the perforations C in the annulus A, and also curved lines of perforations at E and F, the central portions 15 of both of which pass through the center of the disc.

It is assumed, and this assumption is instantly understood without explanation, that the highway, at the side of which the sign is to be installed, proceeds vertically through the center of the disc. If the railroad or intersecting highway approaches the intersection from its horizon location in a curve, a suitable curved line is chosen and brought opposite the horizontal location in 20 the annulus and in the perforations in the line, reflectors are inserted. The opposite segment of the intersecting highway from the intersection to the other horizon point, is likewise filled with reflectors.

The disc and annulus are secured in adjusted relation by screws G as shown in Fig. 2.

I have illustrated in Figs. 5 and 6 various relations of highways to railroads which may be easily indicated by the adjustment of my sign. If it is 35 desired to show the location of the highway by which the sign is located it may be painted in as shown at H in Figs. 5 and 6. If the amount of traffic in the highway justifies or requires the expenditure, the reflectors in my sign may be 40 replaced by either flashing or continuously burning electric lights.

Having described my invention, what I claim and desire to secure by Letters Patent is:

1. A sign having a peripheral portion with 45 means for indicating thereupon the horizon origin of intersecting roads and a central portion, adjustable with respect to said peripheral portion, provided with radial and curvilinear lines of means indicating the intersection of such roads 50 at the center of said central portions.

2. A sign having a peripheral portion with 55 spaced apertures therein adapted to receive reflectors indicating the horizon location of intersecting roads, and a central disc provided with

radial and curvilinear rows of apertures passing through the center of said disc, also adapted to receive like reflectors connecting the horizon designating reflectors located in said peripheral portion, said central and peripheral portions having adjustment with respect to each other.

3. A sign for indicating the relation of intersections of a highway with a railroad or another highway comprising an annular peripheral portion having apertures for the receipt of light dis-

persing elements at spaced intervals for designating the horizon locations of the intersecting ways and a central portion provided with radial and curvilinear lines of apertures adapted to receive like light dispersing elements, connecting pairs of said peripheral apertures through the center of said central portion and means for securing said peripheral and central portions in adjusted relation.
